(57) **CLAIM**

The ornamental design for motion isolation insulator pad, as shown and described.

DESCRIPTION

FIG. 1 is a top perspective view of the motion isolation insulator pad;

FIG. 2 is a top perspective, close-up view of the motion isolation insulator pad of FIG. 1;

FIG. 3 is a top view of the motion isolation insulator pad of FIG. 1;

FIG. 4 is a bottom view of the motion isolation insulator pad of FIG. 1;

FIG. 5 is a front side view of the motion isolation insulator pad of FIG. 1;

FIG. 6 is a rear side view of the motion isolation insulator pad of FIG. 1;

FIG. 7 is a right side view of the motion isolation insulator pad of FIG. 1; and,

FIG. 8 is a left side view of the motion isolation insulator pad of FIG. 1.

Broken lines in FIG. 1 are for illustrative purposes only and do not form part of the claimed design. View designating arrows and associated numbers in FIG. 1 are for illustrative purposes only and do not form part of the claimed design.
